PRICE MARKING TAG AND METHOD OF
MAKING THE SAME

Louis Fox, Los Angeles, Calif.

Application April 13, 1936, Serial No. 74,038

4 Claims. (CL. 40—2)

My invention relates to price marking tags, tickets, labels, and stickers, and particularly to an article of manufacture and the method of making the same for making pressure sensitive adhesive or gum units for the manufacture of such price marking tags, tickets, labels, and stickers.

My invention more particularly relates to labels or price marking tags, tickets, or stickers adapted to be applied to articles or goods through the medium of a pressure sensitive adhesive and to a method of making such price marking tags, etc.

Throughout this specification and for the sake of brevity the term label is meant to include a price marking tag, ticket, and sticker.

An object of my invention is to provide a novel label which may be put up in rolls that are adapted to be fed through any of the conventional labeling machines or in which the label may be manually removed from the roll and manually applied to the article to be tagged or marked.

An object of my invention is to provide a novel label wherein a plurality of labels are connected end to end to form a continuous chain as distinguished from individual labels separately mounted (if at all) on a separate mounting strip without any other connecting means than such mounting strip.

Another object is to provide a novel label that is simple and economical of manufacture.

Another object is to provide a novel unit that may be used in the manufacture of labels.

A still further object is to provide a novel unit whereby pressure sensitive labels may be economically manufactured and adapted for use in connection with machines at present used in the manufacture of such labels.

A still further object is to provide a new and useful method of manufacturing pressure sensitive adhesive labels either with or without printed matter thereon.

A still further object is to provide a novel method of manufacturing pressure sensitive adhesive and protected labels wherein the labels may be formed, printed and otherwise prepared while attached one to the other.

Other objects, advantages, and features of invention may appear from the accompanying drawing, the subjoined detail description and the appended claims.

The accompanying drawing illustrates the invention in some of the forms I at present deem preferable.

Figure 1 is a fragmentary view of a pressure

sensitive gum unit used in the manufacture of price marking tags, tickets, labels and stickers, in accordance with my invention. The non-adhesive covering is partially broken away to expose the rows of pressure sensitive adhesive thereunder.

Fig. 2 is a view analogous to Fig. 1 but illustrating a unit having a different number of pressure sensitive adhesive rows thereon.

Fig. 3 is a fragmentary view of the unit shown in Fig. 1 but viewed from the reverse side thereof and showing the unit perforated and partially prifited.

Fig. 4 is a view analogous to Fig. 3 but showing the same cut or slit to form a plurality of individual rows of labels. The rows have been separated from each other along the line of cutting to more fully disclose the individual structure.

Fig. 5 is a view of a plurality of finished labels but looking from the reverse side of Figs. 3 and 4 and showing the non-adhesive covering partially raised to disclose the pressure sensitive adhesive on the label.

Fig. 6 is an enlarged transverse sectional view taken on line 6—6, Fig. 5.

Fig. 7 is a view of a price marking tag in its finished form and viewed as applied to an article.

In carrying out my novel method of making a pressure sensitive price marking tag, ticket, label, and sticker, including the unit in connection therewith, I first take a strip of suitable material 1 which is of a predetermined width and elongated to an indefinite length such as a tape and which is of a suitable character to receive and retain on its surface a pressure sensitive adhesive *a* which is of a non-drying character. The pressure sensitive adhesive *a* is arranged on the strip 1 in a series of rows 2 that extend longitudinally of the strip 1 and which rows are spaced thereacross and separated by narrow uncoated portions 3 of substantially equal width. The rows 2 of pressure sensitive adhesive *a* are also of substantially equal width and may be of any predetermined number, and as shown in Fig. 1, there are 5 rows spaced across the strip 1, and as shown in Fig. 2 there are 4 rows of the pressure sensitive adhesive spaced across the strip 1. The difference in the width of the pressure sensitive adhesive rows 2 provides for making wider or narrower labels that are adapted to be used in standard label attaching machines.

The pressure sensitive adhesive *a* is preferably of the type known as a pressure sensitive gum or adhesive and which is non-drying and which will adhere to most surfaces sufficiently strong enough to retain the label in place, but which adhesive

permits removal of the label without damage to the goods or surface upon which it was applied.

A non-adhesive covering 4 which is in substantially the same form as the strip 1 forms a backing 5 of protective material over the rows of the pressure sensitive adhesive *a* and such non-adhesive covering may be either Cellophane, holland cloth, glassine or any other treated or similar material which may be removed from the strips or rows 2 10 of the pressure sensitive adhesive *a* without likelihood of the adhesive adhering thereto and being removed from the strip 1.

The multiple label blank unit A thus formed is then perforated at spaced intervals along the strip 1 in predetermined distances that determine the length of the label and such perforations may be of any suitable size or shape such as the polygonal perforations 5 that extend in columns along the uncoated portions 3 and which perforations 5 20 delineate the corners of the individual label unit 6. The perforations 7 that are preferably centered in the rows 2 of the pressure sensitive adhesive *a* are formed simultaneously with the perforations 5 and such perforations 7 may be rectangular as shown or of any other desired contour suitable to conform to the feeding mechanism of 25 mechanical label machines, and also further aid in weakening the junctions between the ends of the label units so as to permit easy separation one 30 from the other. In some labeling machines the strips of labels are fed therethrough by mechanism engaging the notches *b* that are formed by the perforations 5 in the longitudinal sides of the labels and it is apparent that such perforations 5 35 may be of any desired contour or size to adapt themselves for use with the labeling machine adapted to feed labels therethrough by engagement with such notches *b*. The small perforations 8 connecting the perforations 5 and 7 insures 40 easy and accurate separation of individual label units 6 one from the other.

During this perforation of the label blank, the label units are usually printed with suitable indicia 9 to indicate the establishment in which they are 45 to be used. However, it is apparent that such indicia 9 may be subsequently applied to the label units after the step of perforating the same.

The label blank A is then cut longitudinally 50 along the columns of perforations 5 as at *c* thereby forming strips 10 of individual label units 6 that are connected in independent rows at their ends to adjacent label units.

By cutting the label unit A as above set forth it will be seen that the cuts *c* are made along the 55 centers of the uncoated portions 3 thereby forming a label unit 6 that is provided with edge portions 11 that are uncoated and which enables a person to easily separate the protective backing material 4 from the strip 1 when it is desired to 60 remove the protective backing material from the pressure sensitive adhesive *a*.

In order to accurately form each strip 10 of a predetermined width and shape the longitudinal edges of the strip 4 are provided with portions *d* 65 that are discarded after slitting or cutting the label blank by the cuts *c*.

The labels may then be printed with any suitable indicia 12 as shown in Fig. 7 to indicate the stock number, size or price, or any other data desired thereon, and the strips 10 are then rolled

up into rolls containing the predetermined number of label units after which they may be applied to articles, either manually or through mechanical labeling machines.

In summation, my method of forming labels of this type consists essentially in applying to one side of an elongate sheet a plurality of spaced rows of pressure sensitive adhesive and which rows are separated by relatively narrow uncoated portions; then applying a non-adhesive covering or 10 protective backing material to the pressure sensitive adhesive; then perforating the blank and covering, transversely and longitudinally of the strip and applying indicia to one side of the sheet; then separating the combined sheet and covering 15 into strips or columns of individual label units in such a manner that the side margins of the covering are free of the sheet; and then printing price indicia thereon.

My invention also includes the articles shown in 20 Figs. 1 and 2 and which are supplied in rolls to printers of price tags who are equipped with special machinery for that purpose as well as the complete method hereinbefore set forth.

I claim:

1. A label strip comprising; a plurality of label units attached end to end to form a continuous strip, an adhesive covering at least part of the back of said label units, a non-adhesive backing for the adhesive continuous therewith and of 30 greater width to form a free margin, and aligned spaced feeding apertures extending between the label units and through the backing, said label units having weakened portions, and said covering forming a reinforcement for said label units 35 at the weakened portions thereof.

2. A label strip comprising; a plurality of label units attached end to end to form a continuous strip, an adhesive covering at least part of the back of said label units, a non-adhesive backing 40 for the adhesive continuous therewith and of greater width to form a free margin, and aligned spaced feeding apertures extending between the label units and through the ungummed portion thereof, and through the backing, said label units 45 having weakened portions, and said covering forming a reinforcement for said label units at the weakened portions thereof.

3. A label strip comprising; a plurality of label units removably attached end to end, a continuous strip of adhesive extending along the label strip, a backing for protecting the adhesive and reinforcing said label units, and having a greater width than the strip thereof to provide a free margin, and notches extending between the label 55 units and through the backing at the corners of said label units.

4. A label strip comprising; a plurality of label units attached end to end to form a continuous strip, an adhesive, covering at least part of the backs of said label units, a non-adhesive backing for the adhesive covering said adhesive on the backs of said label units, and aligned spaced feeding apertures extending between the label units and through the backing, said label units having weakened portions, and said covering forming a reinforcement for said label units at the weakened portions thereof.

LOUIS FOX. 70
